UNITED STATES PATENT OFFICE.

CARLISLE H. BALDWIN, OF NEW BRITAIN, CONNECTICUT, ASSIGNOR TO THE CORBIN CABINET LOCK COMPANY, OF NEW BRITAIN, CONNECTICUT, A CORPORATION OF CONNECTICUT.

DESIGN FOR A MAIL-BOX.

42,095.

Specification for Design.

Patented Jan. 16, 1912.

Application filed October 9, 1909. Serial No. 521,961. Term of patent 7 years.

To all whom it may concern:

Be it known that I, CARLISLE H. BALDWIN, a citizen of the United States, residing at New Britain, in the county of Hartford and State of Connecticut, have invented a new, original, and ornamental Design for a Mail-Box, of which the following is a specification, reference being had to the accompanying drawing, forming part hereof.

Figure 1 is a view in front elevation of the box. Fig. 2 is a view in side elevation.

A characteristic feature of my design resides in the box the front and sides of which present a substantially plain surface from side to side, the meeting corners, however,

being slightly rounded, the box thus having a plain appearance but the rounding of the corners relieving a sharp angular form. This taken in connection with the flat top having a thin projection on all sides combined with the plain arrangement of the box gives to the whole structure an extremely plain and neat appearance.

I claim—

The ornamental design for a mail box, as shown and described.

CARLISLE H. BALDWIN.
